COMBINED RADIO, PHONOGRAPH AND SPEAKER CABINET

Ryoichi Takeoka, Tokyo, Japan, assignor to Matsushita
Electric Industrial Co., Ltd., Kadoma, Osaka, Japan

Filed Oct. 10, 1972, Ser. No. 296,403

Claims priority, application Japan Apr. 10, 1972

Term of patent 14 years

Int. Cl. D14—01

U.S. Cl. D56—4 C

FIG. 1

FIG. 2

FIG. 3

FIG. 4

FIG. 5

FIG. 6

FIG. 1 is a front, top and right side perspective view of a combined radio, phonograph and speaker cabinet showing my new design with the lid in raised position;

FIG. 2 is a front, top and right side perspective view with the lid in closed position;

FIG. 3 is a rear, top and left side perspective view thereof;

FIG. 4 is a right side perspective view thereof;

FIG. 5 is a right side perspective view thereof with a separable speaker portion transposed to one side; and

FIG. 6 is a top plan view thereof.

I claim:

The ornamental design for a combined radio, phonograph and speaker cabinet, as shown and described.
